UNITED STATES PATENT OFFICE.

ANDREW J. STORHOW, OF ELMA, WASHINGTON, ASSIGNOR TO C. H. COLSON, INC., OF ELMA, WASHINGTON, A CORPORATION OF WASHINGTON.

CONTAINER.

Application filed December 14, 1926. Serial No. 154,754.

This invention relates to containers and more particularly to a container for materials which are to be gradually dispensed or sifted therefrom.

5 An important object of the invention is to provide a container of such shape that it may be readily held in the hand while shaking the container to dispense the contents and so interiorly formed that the contents 10 are readily directed toward an opening formed in the wall thereof.

A further object of the invention is to provide a device of this character which may be very readily and cheaply constructed and 15 which is capable of shipment while knocked down for assembly at the factory where it is to be employed.

These and other objects I attain by the construction shown in the accompanying 20 drawings, wherein for the purpose of illustration is shown a preferred embodiment of my invention and wherein:—

Figure 1 is a plan view of the blank from which the container is formed;

25 Figure 2 is a perspective view of the container;

Figure 3 is a section on the line 3—3 of Figure 2;

30 Figure 4 is a section on the line 4—4 of Figure 2;

Figure 5 is a section on the line 5—5 of Figure 2;

35 Figure 6 is a perspective view of the corner of the container with the indicated portion cut away to provide an outlet opening;

Figure 7 is a sectional view taken through the blank as folded for shipment.

Referring now to the drawings and more 40 particularly to Figure 1 thereof wherein is disclosed a blank for the construction of a container in accordance with my invention, the numeral 10 generally designates a central panel which is relatively narrow and 45 which has connected thereto along its side edges large panels 11 and 12 of the same length as the panel 10, but considerably broader. The panels 11 and 12 are preferably of the same width and one of these 50 panels has at its free edge a flap 13 adapted to be secured to the free edge of the other of the large panels, so that a triangular tube is formed. Each large panel 11 and 12 has secured to its upper and lower end edges 55 a triangular flap 14 having its sides of the

same length as the width of the panels 11 and 12 and its base of the same length as the width of the panel 10. The panel 10 has at its upper and lower end edges similar triangular panels 15 which are truncated, as at 16, so that they have a length from this truncated edge to the adjacent edge of the panel 10 equal to the length of a perpendicular drawn from the attached edges 17 of the triangular flaps 14 to the free apices 18 thereof. This edge 16, therefore, aligns with the apices 18, thus reducing the waste incurred in the formation of the blanks, and by truncating the flap 15, there is less material to cut through in removing the corner 65 of the box.

In assembling the container, the flap 13 is first secured to the free edge of the other of the large panels after which one end of the box is closed by folding in the flap 15, then 75 one of the flaps 14, securing these flaps together and then folding the second flap 14 at its end in upon the first flap 14 and securing it to this flap. By truncating the flap 15 it provides for the pasteur to insert his finger 80 under the flap and thus forming a solid base for pasting down next flap. An open topped box is thus produced into which the material may be introduced. After the material has been introduced, the top of the 85 box is closed in a similar manner.

In the construction of the blank, the free corner at the upper edge of each of the large panels is provided with a mark 18; setting off a small triangular corner of the panel 14 and the adjoining portion of the flap 14 which is to be arranged uppermost is provided with a line 19 which, in the assembled 90 relation of the container, connects the upper ends of the lines 18 and combines therewith to provide an indicating mark forming a 95 guide for cutting away a corner of the container through which the contents may be delivered. By cutting away this corner, an opening is formed at one end of the triangular tube and in the end wall thereof and at the minor angle of the tube. The base of the triangle formed by the panel 10 being relatively narrow may be readily grasped in the hand to dispense the contents of the container through the opening thus formed. By folding the flaps 13, 14 and 15 upon the same face of the panels 10, 11 and 12 and then folding the panel 12 to which the flap 13 is secured back upon the faces of the panels 100 105 110

10 and 11, as indicated in Figure 7, all of the flaps will be held against movement with relation to the panels and a flat unit provided which is readily stored for shipment 5 to the factory.

Such a container may be very cheaply produced and is readily assembled. Since the construction thereof is capable of a certain variation, I do not limit myself to the structure hereinbefore set forth except as herein- 10 after claimed.

I claim:—

A container comprising top and bottom 15 ends and a body, the body having three sides, one of which is relatively narrow to permit the edges thereof to be conveniently gripped between the thumb and fingers of the hand, the remaining sides and top of the box in

conjunction therewith and at the upper corner of the box having coacting lines indicating a portion of the container to be removed to produce an outlet for the contents, the sides of the container having at their upper and lower end edges triangular flaps, 20 said flaps being connected to the sides along one of the long sides of the triangle to overlay each other and being pasted to each other to thereby close the ends of the container, the flaps of the narrow sides being truncated in alinement with the free apices 25 of the flaps of the wider sides, whereby said last named flaps terminate short of the corner which is to be cut away.

In testimony whereof I hereunto affix my signature.

ANDREW J. STORHOW.
